ADJUSTABLE BRACKET AND FILTER FOR HOME AQUARIUMS

David D. Lovitz, Short Hills, N.J., assignor to Sternco
Industries, Inc., Harrison, N.J.

Filed Dec. 22, 1971, Ser. No. 211,158

Term of patent 14 years

U.S. Cl. D23—4
Int. Cl. D23—01

FIG. 2

FIG. 1

FIG. 5

FIG. 4

FIG. 3

FIG. 1 is a top perspective view of an adjustable bracket and filter for home aquariums showing my new design.

FIG. 2 is a front view thereof.

FIG. 3 is a side view thereof.

FIG. 4 is a rear view thereof.

FIG. 5 is a bottom view thereof.

I claim:

The ornamental design for an adjustable bracket and filter for home aquariums, as shown.
